UNITED STATES PATENT OFFICE.

IRWIN W. MILLARD, OF CHICAGO, ILLINOIS, ASSIGNOR TO INDUSTRIAL GLOVES CORPORATION, OF CHICAGO, ILLINOIS, A CORPORATION OF DELAWARE.

LEGGING.

Application filed September 21, 1925. Serial No. 57,483.

To all whom it may concern:

Be it known that I, IRWIN W. MILLARD, a citizen of the United States, residing at Chicago, in the county of Cook and State 5 of Illinois, have invented a certain new and useful Legging, of which the following is a specification.

More particularly the invention relates to a legging adapted to be used by foundry- 10 men, blacksmiths and other workmen for protection against injury from flying particles of molten metal, etc., or from the heat of nearby intensely hot objects.

It is the object of the invention to provide 15 a new and improved legging of a construction particularly adapted to afford perfect freedom of movement of the foot relative to the leg without discomfort and at the same time to form an effective close-fitting 20 covering for the foot as well as the leg.

In pursuance of the foregoing and other 25 objects, I aim to provide a legging comprising a covering of leather or other suitable flexible material, having an upper portion 30 reinforced in a manner to cause the legging to properly grip the leg without the use of fastening devices, a second or intermediate portion of flexible material adapted to lie adjacent the ankle, this portion being stiffened 35 along the side edges only, and a third or lower portion also of flexible material providing a flare to overlie the shoe.

Further objects and advantages of the 40 invention will be understood from the following detailed description taken in connection with the accompanying drawings, in which:

Figure 1 is a plan view of the preferred 45 form of my invention (expanded).

Fig. 2 is a side view thereof.

Fig. 3 is a section on an enlarged scale 50 along the line 3—3 of Fig. 2 looking in the direction of the arrows.

Fig. 4 is a view of the metal frame (expanded).

Referring to the accompanying drawings, the invention in the exemplary form illustrated has an upper portion 1, an intermediate portion 2 and a flare 3, the portions 1 and

2 comprising a flexible covering 4 of leather 50 or other suitable material, a lining 5 and a metal frame, the frame lying between the cover and lining and being adapted to support the covering and to shape the legging to the leg of a wearer.

In the preferred embodiment, this metal frame comprises a pair of vertical side ribs or stays 6, a shorter centrally positioned stay 7, and two U-shaped spring steel hoops or clips 8 and 9, the said stays and clips being 60 riveted together with one clip positioned transversely of the stays at their upper ends and the other clip forming a transverse member of the frame at the lower end of the shorter stay as shown in Fig. 4. The 65 frame is so proportioned that when fitted around the leg of a wearer the lower clip 9 is 70 a substantial distance above the ankle.

As illustrated herein, the covering for the 75 legging comprises the suitably shaped sheet 70 of flexible leather 4, the somewhat similarly shaped canvas lining 5 and two flexible leather tabs, one tab forming the flap 12 and the other the hereinbefore mentioned flare 3. The flap 12 may be sewed to one edge of the 75 legging as shown in Fig. 1, this flap being adapted to fit around the back portion of leg of the wearer to be tucked inside the opposite edge of the legging as shown in Fig. 3, to protect the back of the leg. The 80 flare 3 is secured to the lower end of the intermediate flexible portion 2 to overlie the shoe.

These component parts of the covering 85 and the metal frame may be assembled together by different methods, the preferred method being as follows: A slightly arcuate strip of leather 13 is sewed along the upper edge of the cover 4, the arcuate shape serving to draw the top edge of the strip inwardly as shown in Fig. 2 to hug the leg of the wearer and thereby prevent particles from entering the legging around the top. The lining 5 is then placed centrally on the inner surface of the leather cover 4, and the side edges of the leather and ends of the strip 13 folded inwardly as shown in Fig. 3.

Side seams 14 and 15 and a transverse

seam 16 may then be sewed through the leather and canvas to thereby form a pocket within the covering adapted to receive the metal frame. The flap 12 is sewed to one side edge of the covering and the flare 3 sewed to the lower edge of the intermediate portion 2 by a seam 17. This seam is preferably reinforced as by U-shaped metal clips 18 which penetrate both leather portions and lining and are secured in the usual manner, and serves to close the lower ends of the portions 19 of the pocket formed between the cover and lining.

It will be evident that the above mentioned assembly operations may be performed before the metal frame is inserted in the covering, thereby facilitating the work by permitting the sewing to be done while the materials will lie flat. The metal frame 20 as a unit is then inserted between the cover 4 and lining 5, the lower extending portions 6^a of the stays entering the portions 19 of the pocket and the clip 9 lying adjacent the seam 16.

25 Inner side seams 20 above the clip 9 are then sewed through the two layers of leather and the lining on the inner side of the stays 6 to secure the said stays in position adjacent the edges of the legging, and a seam 21 is sewed across the top of the legging through the strip 13, cover 4 and lining 5 to prevent the frame from moving upwardly in the covering. The strip 13 may be folded inwardly at its upper edge and stitched as at 30 22 to reinforce and finish that edge.

When properly fitted to a wearer's leg with the flap 12 wrapped around the leg and the clip 8 around the upper portion of the calf of the leg, the tension of the spring clips acting upon the side stays 6 effectively holds the legging in position. The top strip 13 then hugs the leg closely and the lower clip 9 is positioned substantially above the ankle to provide the intermediate flexible portion 2 below the clip and forward of the ankle in addition to the flexible flare 3 which overlies the shoe. It will be apparent that with this construction wherein the entire front portion of the legging up to a point substantially above the ankle, is flexible, the wearer is afforded perfect freedom in bending his ankle whereas the metal frame with the side stays extending to the lower edge of the covering effectively retain the legging in position.

I claim as my invention:

1. A legging having, in combination, a metal frame shaped to fit a wearer's leg, said frame comprising a pair of longitudinal side stays, a shorter central stay, and a plurality of spring clips, said spring clips being spaced one above the other transversely of said stays, a flexible cover, a flexible lining, said frame being inserted between said cover and lining and secured therebetween by

seams through the cover and lining adjacent edges of the frame members, the lowermost of said clips being positioned a substantial distance above the ankle, the said side stays and cover extending below said clip, the portion of the cover below said clip and between the side stays forming a flexible covering for the ankle, and a flexible flare secured to the lower edge of said covering and adapted to overlie the foot.

2. A legging having, in combination, a metal frame shaped to fit a wearer's leg, said frame comprising a pair of longitudinal side stays, a shorter central stay, and a plurality of spring clips, said spring clips being spaced one above the other transversely of said stays, a flexible cover, a flexible lining, said frame being inserted between said cover and lining and secured therebetween by 80 85 90 95 100 105 110 115 120 125 130

seams through the cover and lining adjacent edges of the frame members, the lower of said clips being positioned a substantial distance above the ankle, the said side stays and cover extending below said clip, the portion of the cover below said clip and between the side stays forming a flexible covering for the ankle, a flexible flare secured to the lower edge of said covering and adapted to overlie the foot, a flexible flap extending from one side edge of said cover and adapted to surround the back portion of the leg, and an arcuate strip of flexible material secured to the top edge of the cover and adapted to hug the leg.

3. A legging having, in combination, a flexible covering, a flexible lining, a metal frame secured between said cover and lining, said frame comprising longitudinal stays and transverse spring clips and being adapted to stiffen the upper portion of the legging and to detachably secure the legging to a wearer's leg, a flexible flare secured to the lower edge of said cover, there being a portion of said cover between said flare and the lowermost of said clips, which portion is adjacent the ankle and is stiffened only at the rear edges thereof, thereby providing a flexible covering about the ankle.

4. The method of manufacturing a legging which consists of sewing an arcuate strip of flexible material 13 along the upper edge of a suitably shaped flexible cover 4, placing a similarly shaped flexible lining 5 on said cover, folding in the side edges of said cover, sewing longitudinal side seams 14 and 15 and transverse seam 16 to form a pocket between the cover and the lining, sewing a flexible flare 3 along the lower edge of the cover, sewing a flexible flap 12 along one side edge of the cover, inserting a unitary metal reinforcing and shaping frame in the said pocket and sewing additional seams along the members of said frame to secure the frame in the covering.

5. The method of making a legging which

consists of placing a suitably shaped flexible lining on a similarly shaped flexible cover, folding inwardly the side edges of the cover, sewing seams through said cover and lining to form a pocket therebetween, securing a flexible flare to the lower edge of said cover, inserting a unitary metal reinforcing and shaping frame in said pocket, and sewing additional seams through said cover and lining to secure the cover and lining 10 stretched on the frame.

In testimony whereof, I have hereunto affixed my signature.

IRWIN W. MILLARD.
